UNITED STATES PATENT OFFICE.

GEORGE SCOTT CHILES, OF CHICAGO, ILLINOIS.

SIDE-FRAME CONSTRUCTION FOR RAILWAY CARS.

Application filed May 17, 1921. Serial No. 470,464.

To all whom it may concern:

Be it known that I, GEORGE SCOTT CHILES, a citizen of the United States, and a resident of Chicago, in the county of Cook and State 5 of Illinois, have invented a new and useful Improvement in Side-Frame Construction for Railway Cars, of which the following is a specification.

My invention relates chiefly to the peculiar 10 construction of a cast steel side frame and the spring equipment used therewith in a railway truck bolster, but fabricated frames may also be used with this construction.

The object of the invention is to improve 15 the spring equipment involved in carrying the load and to improve the distribution of the metal involved in the construction of the side frame to produce greater economy in weight and cost, and secure greater strength 20 and efficiency of the structure.

Reference will be had to the accompanying drawings in which Figure 1 is a side elevation of a car truck with the journal boxes omitted and showing the wheels and axles 25 only in diagram. Figure 2 is a section showing the parts on line 2—2 of Figure 1. Figure 3 is a modified form of the spring fastenings and of the bolster connection to the springs from that shown in Figures 1 and 2.

Figure 4 is a transverse section of the parts shown on line 4—4 of Figure 3. Figure 5 is an enlarged detail of the spring connection shown in Figure 3. Figure 6 is a view looking in the direction of the arrow 35 A of a portion of the edge of the side frame shown in Figure 3, for the sole purpose of showing the hole through which the spring bars are entered. Figure 7 is a modified detail of the bolster end and spring arrangement. Figure 8 is an end view of another 40 form of bolster and coacting part of the side frame. Figure 9 shows the parts on line 9—9 of Figure 8. Figure 10 shows a modified form nearest like the construction shown 45 in Figure 7. Figure 11 is an enlarged section of the lower member of the side frame only on line 11—11 of Figure 10. Figure 12 is a diagrammatical view showing the strain lines involved in side frames as shown by the 50 practice quite generally heretofore used. Figure 13 shows a similar view to that of Figure 12 but as applied to my invention involved in this case.

In the drawing 1 indicates in dotted lines

the outline of the car wheels involved in the 55 truck. 2 indicates the axles. The journal boxes are not shown but they may be of any suitable form or pattern and may when desired be cast integral with the side frame itself.

3 indicates dotted lines, being the vertical 60 central load lines of the bearings on the axles of the wheels. 4 indicates the compression or top girder of the side frame as a general term, referring to the side frame 65 itself. 5 indicates the body of the bolster as a general term for the bolster itself. This truck bolster is what is known as the cast steel bolster but may be of any other suitable form of a bolster having the detailed 70 features either cast integral or fabricated as may be desired as described herein.

With my invention I use what are known 75 as flat bar or leaf springs so arranged that what is ordinarily termed the spring plank, is not necessary or desirable. These spring bars are indicated by 6 and as shown in Figure 2 they are simply flat bars curved as shown in Figure 1 and supported at their 80 ends by a series of steps or offsets 7. The bars are separated as shown at their ends, each having its individual step or seat with clearance between the spring bars as is indicated by 8 but in the central zone, whereon the bolster rides, the several spring bars are 85 pressed in contact with each other under the influence of the load as indicated by 9. When the bars are first made they are shaped so that each separate bar must be deflected slightly, taking some initial load, before 90 the final or lower bar is fixed. However, I may, as desired, so construct them that there is no initial load between each leaf and that each leaf or bar commences to take the load at the same time.

The bolster is provided with end flanges 10 which embrace the spring bars on the side and thus transmit lateral thrust load through the spring bars themselves to the side frame, since the spring bars are embraced at their ends by the side flanges 11 of the tension member 12 of the side frame.

In the construction shown in Figures 1, 2, 8, 9 and 10 the direct line travel thrust or side movement of the bolster is transmitted 105 to the side frame by the projections 13 of the compression member 4 of the side frame and these projections 13 terminate at 14 and thus

there is left an open clear space 15 which permits the spring bars or leaves to be inserted sidewise into their seats in the side frame at a time when the bolster 5 is raised to the upward limit of its position in the side frames.

In Figures 1 and 2 the spring bars 6 will necessarily slide endwise slightly on their steps or seats 7 as the varying loads and 10 shocks produce a movement of the springs and thus there will be a slight frictional movement which is always attendant upon the flexure of leaf springs and this movement serves to act as dampeners or shock 15 absorbers for spring recoil shocks. Further, this sliding of the leaves of leaf springs develops frictional work which aids in absorbing the road shocks for which springs are primarily used as well as absorbing the recoil action. This frictional 20 feature whereby work or energy is dissipated is a matter of much importance in a car structure for it absorbs and dissipates what amounts to an infinite number of 25 small vibrations that occur in the use of a rolling structure.

I obtain a greater frictional work absorption of vibration and spring recoil, known as shock absorbing work, by the 30 modified form of spring mounting shown in Figure 3 and I gain a still greater result in this respect by the modified form of the structure shown in Figures 7 and 10. In Figures 3 and 5 I provide every alternate 35 spring seat or step 7 with a little pocket or recess 16 and I turn over one end of the several spring bars or leaves into an angle projection indicated by 17 which engages the pocket 16 and thus as the spring body is deflected the longitudinal slip or creep of the 40 several bars or leaves is made to travel in one direction. The sum total of the slip or articulation of the several bars upon themselves as every other bar is held fixed at alternate 45 ends amounts to increasing the frictional movement of the spring leaves or bars upon themselves very materially, producing a total frictional movement of upwards of 4 times of what is involved in the arrangement 50 as shown by Figure 1, since in Figure 1 the several spring bars at their center move little or none at all upon themselves and the movement takes place only at the ends, whereas, with the form shown in Figure 55 3 each entire bar is made to move lengthwise on its neighboring bar the full amount of movement caused by the deflection.

The greater frictional work absorbing 60 feature involved in the modified form shown in Figures 7 and 10 is arrived at by making a less number of seats or steps 7 and then making the bars in pairs and letting the free end of each bar ride upon the 65 neighboring bar below it, this arrangement

permitting a longer surface contact of the bars upon each other than is obtained by the other constructions which provides for contact of the bars or spring leaves on each other chiefly in the main central zone under 70 the bolster.

This construction of riding the free ends of the spring leaves or bars upon their neighbors prevents any movement of the bars on the seat 7 and thus avoids any 75 wear that will take place on the surface of the seats 7 as involved in the construction shown in Figure 1 and upon a less number of seats with the construction shown in Figure 3.

By my arrangement of producing spring dampening or shock absorbing effects I am permitted to make this an important commercial factor with little or no additional expense whereas it is troublesome and expensive to get a shock absorbing effect with a coiled spring construction.

The arrangement of my springs as shown wherein the load of the bolster is transmitted as it were by the spring acting as 80 a bridge carrying the load to the side frame in a region closely approaching the ends of the side frame near the bearing load lines 3 amounts to applying the load on the side frame closely to the ends which permits a 85 much lighter side frame construction than where the load is taken approximately in the center region of the side frame. This is more readily appreciated when I say that the old method of loading the side frame with the coil springs or transverse plate springs, located in the central region, 90 amounts to applying a total load of the bridge structure as it were in the center, while with my method, the total load on the bridge structure is divided in two parts 95 and applied closely adjacent the ends so that the stresses that must be taken up by the metal of the side frame are relatively light in the central region of the side frame, whereas with the former constructions the stresses are relatively heavy in the 100 central zone of the side frame.

Thus it is plainly to be seen that with a 105 side frame of my construction having a longitudinal spring said frame may be made with less metal than ordinarily required to take up the load strains.

Further, with the old construction of 110 center applied load on the side frame, the maximum fibre stresses of the metal for the 115 whole load is centered substantially in one zone or cross section of the tension member, which might be in cross section in the bottom section under the bolster whereas, with my arrangement of the springs each individual leaf or bar has a separate point of application of its load to the side frame 120 so that there is no one section which receives 125 as much maximum shock strain as is in-

volved in the old construction. Thus there is only a short zone or section of the side frame metal which must carry the whole load of the tension member and this short zone is the zone indicated by the portion 5 of Figures 1 and 3. The virtue of this feature is best understood when I say that a crack or defect in the metal of the side frame in the lower zone or section indicated 10 by 19, Figures 1 and 3, still permits the side frame to carry its load through the bridging effect of the upper spring bars, whereas the same sort of a fracture or weakness would cause a complete failure of the 15 frame with the old style structure.

With the old style trucks the spring planks are more or less generally used and with those that are rigidly fixed to the side frame there are developed in service frequent 20 twist or torsional strains that put tax or overload on the fibres of the metal. These come in the same zone where there are maximum fibre strains due to the direct loads. With my spring construction any torque or 25 twist is transmitted through the spring bars to the side frame at points sufficiently distant from the center of the bolster to amount to a serious reduction in the fibre stresses, due to torsion and twist induced by the bolster or spring plank.

In the form shown in Figure 1 the bolster 5 is provided with integral flanges 10 cast on the bolster as I have previously described, but with the structure shown in Figures 3, 35 4, 7 and 10 the bolster is provided with only narrow flanges 20 and 21 and they embrace spring saddle blocks 22. The blocks 22 are slightly different as relates to those shown in Figures 3, 4, 7 and 10. On the said 40 blocks in Figures 3 and 4 I have curved the lower flange 23 and with the blocks used in Figures 7 and 10 the lower flange has corners 24 making a wider contact on the sides of the spring bars. Further with the blocks 45 22 shown in Figures 7 and 10 there are provided side flanges or shoulders 25 which embrace the ends of the bolster 5 on the sides thereof. In the structure shown in Figures 1, 2 and 3 the sides of the bolster furnish 50 the sliding contact for the vertical movement of the bolster in the side frame as for side thrusts and wear on the bolster. In the structure shown in Figures 7 and 10 the block 22 through its side walls 26 bears 55 upon guides 27 projecting upward from the tension member and the bolster bears upon the guides 13 projecting downward from the compression member.

The structure shown in Figures 3, 4 and 60 6 has the side guides for the bolsters in the form of what are known as the ordinary columns of a side frame, indicated by 28, and because of this fact I must provide the bolster opening indicated by 29 for the entrance and removal of the bolster in this

structure substantially in the manner of the old methods. However, with the use of the columns 28 there is permitted no clearance space 15 as previously described through which the spring bars may be entered 70 in the side frame and therefore I provide an aperture 30 in the side wall 31 of the tension member as is indicated by Figure 6 which must be in one end of the side frame or may be in both as desired. To 75 accommodate for the metal omitted for this aperture 30 I strengthen the side walls as is indicated by 32 in Figure 6.

For the purpose of aiding in supporting the bolster in a direct upright position I 80 provide the two bearing projections 33 on the bolster, shown in dotted lines in Figure 1 and in full lines in Figure 2. These same projections I put upon the block 22 as will be seen by the dotted lines in Figures 7 85 and 10.

The upper or compression member 4 of the side frame is in an inverted channel form as will be more clearly understood from Figure 9 and in order to give a longer 90 vertical bearing in the side guides 13 for the bolster ends I provide a projection 34 at each end of the bolster. The projections 34 are of the full width of the bolster as shown in Figure 8 in order to coact with guides 13, 95 but their dimension lengthwise of the bolster is less than the width of the trough of the channel compression member. Additional vertical guiding surface is thus provided without diminishing the extent of 100 vertical movement of the bolster.

The cross section of the side frame tension member of the frame shown by Figures 7 and 10, is shown by Figure 11, which is on line 11—11 of Figure 10. The arrangement 105 of my springs and side frame as shown and described, brings about a strain sheet or strain line development as is indicated by the diagrammatical view Figure 13 which shows the loads applied on the points 35 as might be applied to an ordinary flexible suspension cord 36. Thus it will be seen that little or no load at all is applied in the central zone 37. Thus the metal is used most 110 efficiently with my design. A comparison with the old structure may readily be made by a study of Figure 12 wherein the commonly used strain line is indicated by 38 and the load applied lines by 39.

This section across the bottom of the side 115 frame of the old design is substantially a beam and also must perform a part of a tie structure as the strain line in this case is tension only on the inclined members and across the bottom there are tension stresses and beam stresses as well which introduce 120 uncertain features as to the action on the metal, for the beam loads react on the column members 40 and also back upon the inclined members 41 as well, but with my 125 130

frame the tension member sustains tension loads only, being the shape assumed by a flexible cord supporting a load as I have described.

5 Thus in the old form the load is substantially mounted in the center and must be carried or transmitted as it were through a larger and longer body of metal to the axles of the wheels, than is the case with my structure as indicated by Figure 13.

10 The less length of material through which the load must be carried is a feature to be desired because of the fact that there is a less factor of chance of weakness in the metal that may cause a fracture in service. Thus my form of transmitting the load from the bolster to the side frame and in turn to the axles of the car, permits as it were a greater factor of safety from weaknesses of 15 foundry practice than may be permitted with the old system of center loading of the side frame. Castings might be inspected and passed for service with weaknesses in the central region of the tension member, 20 with my invention which could not be allowed to pass with the old structure with corresponding weaknesses in the central zone, which is a great desideratum.

What I claim is:—

30 1. In a car truck structure, side frames having compression members and tension members united at the ends of the side frame; in combination with leaf springs extending parallel with the side frames and 35 with their ends separately mounted in seats on the tension member of the side frames and a bolster extending from side frame to side frame and mounted on the said springs.

2. In a truck frame, side frames having 40 compression and tension members, leaf springs extending parallel with the tension members supporting the truck bolster in the middle zone of the leaf springs and the said springs having their ends mounted in a series of steps located in the tension members 45 of the side frames.

3. In a car truck frame, side frames having seats for leaf springs located in the tension members of the side frames and at each 50 end thereof, leaf springs arranged parallel with the side frames and supporting the bolster in the middle zone of the leaf springs and with their ends supported in seats in the tension members of the side frames; in 55 combination with a bolster extending from side frame to side frame and resting on the said springs and guideways in the compression member of the said side frames adapted to hold the said bolster against displacement 60 parallel to the track and for furnishing the vertical sliding guideways.

4. In a truck construction, side frames having a tension member arranged with inclined ends and provided with a series of 65 offset steps or seats adapted to support a

series of spring bars of varying length, each series of bars having an independent step, with the springs composed of separate leaves or bars of varying length and each bar having seats of its own in the tension member of the side frame and the several parts of each spring in contact with each other in the central zone; in combination with a bolster extending from side frame to side frame and resting upon and supported by 70 the said springs in their central zones and mounted to be guided vertically in the side frame.

5. In a structure of the class described, a spring composed of separate bars of varying length and mounted in parallel arrangement with the side frames, separate seats for different bars of the springs arranged in the tension member of the side frame at each end of the springs; in combination 85 with a bolster supported in the central zone of the springs.

6. In a structure of the class described, a side frame arranged to carry leaf springs in parallel arrangement with the side frame 90 and said springs adapted to support a bolster extending from side frame to side frame and the alternate ends of the several leaves that form the said springs secured in the side frames against longitudinal travel of 95 the said ends whereby the flexure of the springs causes a movement of the entire body of each leaf of the springs upon their companion leaves.

7. In a structure of the class described, 100 side frames arranged with seats for leaf springs at each side of the bolster center line; in combination with leaf springs extending parallel with the side frames and adapted to act as a beam across the central 105 zone of the side frame, and different leaves of the said springs having separated seats upon the said tension member, with a bolster extending across from side frame to side frame and supported on the said 110 springs in the central zone thereof.

8. In a structure of the class described, 115 a side frame having a tension member provided with a series of steps or seats for springs arranged on each side of the bolster region, leaf springs bridging the space between the spring seats on the tension member, means for securing the alternate ends of different leaves of the springs in the said seats in the tension member for holding the said ends of the said leaves in longitudinal movement.

9. In a structure of the class described, 120 a leaf spring having alternate ends of different leaves turned over into a projection 125 for securing the said ends from longitudinal movement and the said spring located in parallel arrangement with the side frame and supported therein; with means involved in the seats of the side frame for the said 130

springs, for holding the said turned over ends of the said separate leaves against longitudinal displacement.

10. In a structure of the class described, 5 springs composed of separate bars and the alternate ends of the said bars provided with means for holding them against longitudinal movement; in combination with means for mounting the said springs in the side frames and for holding the several alternate ends of the said bars against longitudinal movement, and means for applying the load of the bolster upon the said springs.

11. In a structure of the class described, 15 a tension member and a compression member forming each side frame, a bolster connected across from side frame to side frame upon which the load of the car is carried, longitudinally arranged springs mounted in each side frame and composed of bars of varying lengths and adapted to carry the weight of the bolster in the central region of the bars and the bars of different lengths having separate seats in the tension member of the side frame and the shorter bars being at the bottom, the said tension member shaped in conformity with a suspension cord strain line running through the contact points of the ends of the spring bars. 20

25 12. In a structure of the class described, side frame members connected across by a bolster and the latter carrying the load of the car, longitudinal springs arranged in the side frames and adapted to carry the ends of the bolster, flanges on the ends of the bolster adapted to embrace the longitudinal springs and thus hold the side frames together transversely of the truck, with vertically arranged guideways in the said frames 30 engaging the sides of the bolster.

35 13. In a structure of the class described, a truck frame composed of side frames and a cross bolster, the latter forming the connecting member between the side frames, longitudinally arranged springs separately 40 mounted at their ends in the side frames and adapted to carry the ends of the bolster in the central body of the springs, projections on the edges of the bolster adapted to bear on the springs in a manner to aid 45 in supporting the bolster in upright position.

50 14. In a truck frame, side frames connected across by a bolster and longitudinally arranged springs mounted in the side frames and adapted to support the bolster in the central body of the springs and the ends of said bolster riding upon the said 55 springs, with bearing points for the bolster

bearing upon the springs at the edges of 60 the bolster and with side flanges extending down the side of the body of the springs for aiding in registering the side frames together.

15. In a truck frame, side frames connected across by a bolster and longitudinally arranged springs mounted in the side frames and adapted to support the bolster in the central body of the springs and the ends of said bolster riding upon the said springs, 70 with bearing points for the bolster bearing upon the springs at the edges of the bolster and with side flanges extending down the side of the body of the springs for aiding in registering the side frames together, and 75 vertically arranged guideways in the side frame for aiding in holding the bolster against movement parallel with the track.

16. In a side frame construction of the class described, a compression member and 80 a tension member united at their ends forming the bridge which carries the bolster load from journal box to journal box, a longitudinally arranged spring composed of spring bars separately supported at their ends in the tension member, guideways for sustaining the bolster against displacement longitudinally of the side frame and said members having clearance space for the admission of the spring parts into their seats in the tension member of the side frame. 85

90 17. In a device of the class described, a side frame having a compression member and a tension member, seats in the tension member assisting to sustain a longitudinal bar spring composed of bars separately supported at their ends in the tension member in parallel relation to the side frame, with a clearance space between the tension member and the compression member which permits the entry of the spring bars laterally 95 into their seats in the tension member of the side frame.

18. In a car truck, side car frames comprising tension and compression members, a bolster, leaf springs supporting said bolster and having their leaves separately supported upon said tension member at their ends and at points out of vertical alinement with said bolster. 100

Signed at Chicago, in the county of Cook 110 and State of Illinois, this 10th day of May, 1921.

GEORGE SCOTT CHILES.
